ROTATABLE DRUM FOR REFINING METALS

Rudolf F. Graef, Oberhausen, Germany, assignor to Hüttenwerk Oberhausen Aktiengesellschaft, Oberhausen, Germany

Application October 15, 1954, Serial No. 462,524

Claims priority, application Germany October 26, 1953

3 Claims. (Cl. 266—36)

The present invention relates to rotary drums for the refining of metals in which the bath is mixed by rotating the drum so that constantly new metal particles are brought into chemical reaction. In addition thereto, also a thorough mixing of the bath in the direction of the axis of the drum is of particular importance. With the heretofore known rotary drums, such mixing is brought about to a certain extent by blowing the refining means upon the bath at an acute angle with regard to the surface thereof, or by introducing the refining means into the bath below the surface of the latter.

It has also been suggested to arrange the axis of the cylinder of the rotary furnace at an acute angle to the horizontal axis of rotation of the furnace so that with each rotation of the furnace, the contents of the furnace are moved to and fro from one end to the other.

The above-mentioned devices have, however, considerable disadvantages. The movement of the bath effected in the direction of the axis of the drum and brought about by the introduction of the refining means or blast is dependent on one hand on the quantity of the refining means or blast which is variable according to the extent to which the blast has been enriched with oxygen, and on the other hand dependent on the quantity of the gaseous oxidation products being formed. Thus, the movement of the bath in the direction of the axis of the drum is greater during the decarburization period than it is during the period in which there is no formation of gaseous oxidation products.

Therefore, it is desirable in the individual phases of the refining process additionally to be able to influence the movement of the bath in the direction of the axis of rotation of the drum. While such additional influencing is possible by arranging the cylinder axis of the drum at an angle with regard to the horizontal axis of rotation, this type of axial bath movement is, however, highly uneconomical. The movement of the bath from one end of the drum to the other is effected by raising the bath at one end so that it flows to the other end. This involves a considerable consumption of energy which is wasted when in this way the to and fro movement of the bath is stronger than required. On the other hand, a variation of the to and fro movement of the bath in a rotary drum with inclined cylinder axis is possible only by varying the speed of rotation. The desired speed of rotation of the rotary drum is, however, dependent on factors other than those appropriate for the axial movement of the bath.

The heretofore known rotary drums provided with a horizontal axis of rotation arranged at an angle to the cylinder axis has the further disadvantages that the angular velocity during the lifting and lowering movement follows a sine curve, and that the frequency of the lifting and lowering movement is completely dependent on the rotative movement of the drum, while the amplitude of the lifting and lowering movement cannot be adjusted.

It is, therefore, an object of the present invention to provide a rotary drum for the refining of metals which will overcome the above-mentioned drawbacks.

2

It is another object of this invention to provide a rotary drum for the refining of metals in which the axial bath movement will be independent of the rotary movement of the drum.

It is a still further object of the present invention to provide a rotary drum of the above-mentioned type, which will make it possible to obtain a lifting and lowering movement of at least one end of the axis of rotation of the drum which will be independent of the rotary movement of the drum about the longitudinal axis thereof, while the amplitude and the frequency of the lifting and lowering movement may be varied independently of each other, and which will also make it possible to obtain a lifting and lowering movement at a completely lineal angular velocity.

A still further object of the invention consists in the provision of a rotary drum of the type set forth in the preceding paragraph which will avoid any possible dangerous sympathetic or resonant variations of the bath.

These and other objects and advantages of the invention will appear more clearly from the following specification in connection with the accompanying drawings, in which:

Fig. 1 represents a longitudinal section through a rotary drum according to the invention.

Fig. 2 is a section taken along the line II—II of Fig. 1.

General arrangement

The present invention is characterized primarily in that at least one end of the axis of rotation of the refining drum is adapted during the rotative movement of the drum to be lifted or lowered independently of the rotary movement of the drum.

According to a further development of the invention, the amplitude and/or the frequency of the lifting or lowering movement is variable. This variability may be brought about by any known means. Thus, for instance, the lifting and lowering movement may be effected by the piston of a hydraulic cylinder adapted periodically to receive and discharge variable quantities of a pressure fluid means so that the stroke of the piston will be variable and the filling and emptying of the cylinder may be effected at a slower or faster rate. The amplitude and the frequency of the lifting and lowering movement may furthermore be varied by causing an electric motor to effect a lifting and lowering movement through the intervention of a transmission, the speed of rotation and direction of rotation of which may be varied independently of each other.

Structural arrangement

Referring now to the drawing in detail, the rotary drum 1 rests on rollers 2 by means of running crowns 3, said rollers being journaled in a base 4. The drum 1 is provided with a toothed ring 5 adapted to mesh with a corresponding gear of a driving motor (not shown in the drawing) which will rotate the rotary drum 1 about the longitudinal axis thereof.

One end of the base 4 rests on rocker bearings 6. Pivotedly connected to the other end of the base 4 at 8 is a hinged support in form of a threaded spindle 7. This hinged support meshes with and is guided by a nut 9 which is rotatably journaled in a casing 10. The casing 10 in its turn is tiltably mounted on a bearing 11. The outer circumference of the nut 9 is provided with teeth meshing with a worm 12 of a driving motor M, which may be an electric motor. When this motor is actuated, the worm 12 turns the nut 9 so that the hinged support or threaded spindle 7 is screwed out of the nut 9 or screwed into the same, thereby lifting or lowering the base 4 together with the drum 1, so that the base 4 and, consequently, also the drum carries out a tilting move-

ment about the axis of the rocker bearing 6. By varying the direction of rotation of the driving motor for the worm 12, for instance, by reversing the poles of the electric motor M drivingly connected to worm 12, the base 4 will be alternately lifted and lowered. The reversing of the poles of the electric motor M may be effected automatically in a manner known per se by limit switches. To this end, abutments 18 and 21 are provided for cooperation with a three pole reversing switch 19 of any standard construction. The abutments 18 and 21 are connected in any convenient manner to the base plate 4 so as to move upwardly and downwardly therewith. As a result thereof, the element 19a of the pole reversing switch 19 is alternately and automatically moved upwardly and downwardly, thereby alternately reversing the field, and thus the direction of rotation of motor M. The frequency of the lifting and lowering movement is variable by controlling or adjusting the speed of rotation of the driving motor in the well known manner by variable resistors 20, while the amplitude of the lifting and lowering movement is controlled by adjusting the abutments 18, 21 which limit the lifting or lowering movement and reverse the poles. The abutments 18 and 21 are fixedly but adjustably mounted on a spindle 22 and rod 23. The spindle 22 is held by a holder 24 connected to rod 23 in any convenient manner, e. g. by a screw 25.

For the sake of completeness, Fig. 1 also shows a blowing nozzle 12' which extends through the drum opening 1a into the metal bath below the layer of slag thereon. The nozzle 12' is carried by a slide 13 movable and adjustable on a track 14. The track 14 is pivotally connected at 15 to a carriage 16. It will thus be seen that the nozzle 12' may be tilted into a horizontal position and by means of the carriage 16 can then be withdrawn from the drum. The tiltability of the track 14 makes it possible to vary the angle at which the nozzle 12' extends into the metal bath thereby causing the nozzle to extend more or less into said metal bath.

The gaseous oxidation products which form during the refining process are withdrawn through the opening 1b provided in the drum 1. The refined metal may be withdrawn from the drum through the discharge passage 17. It is, of course, necessary for discharging the metal from drum 1 that at the time of desired discharge, the passage 17 is moved into its lowermost position. By turning the drum 1 so that the discharge passage 17 is just above the surface of the slag and then slowly rotating the drum in a direction in which the passage 17 moves to a lower level, the slag can also be discharged through the passage 17.

The drum 1 is charged through the opening 1a after the nozzle 12' together with the carriage 16 has been withdrawn from opening 1a.

It is, of course, understood that the present invention is, by no means, limited to the particular construction shown in the drawings, but also comprises any modifications within the scope of the appended claims.

What I claim is:

1. An arrangement for use in connection with the refining of metals in a rotatable reaction chamber, which comprises in combination: a supporting member arranged for rotatably supporting said reaction chamber, fixed

bearing means tiltably supporting one end portion of said supporting member, lifting and lowering means operatively connected and linked to the other end portion of said base member and arranged alternately and continuously to lift and lower said other end portion of said base member while tilting said base member about said fixed bearing means, reversible electric means operatively connected with said lifting and lowering means and operable to actuate the same, and limit switch means associated with said motor means and operable automatically in response to the tilting movement of said base member for alternately reversing the polarity of said motor means.

2. An arrangement for use in connection with the refining of metals in a rotatable reaction chamber, which comprises in combination: a base member, roller means carried by said base member and arranged for rotative movement for rotatably supporting said reaction chamber, fixed bearing means tiltably supporting one end portion of said base member to allow tilting of said base member about an axis transverse to the axis of rotation of said roller means, lifting and lowering means pivotally connected to and supporting the other end portion of said base member for selectively alternately and continuously tilting said base member about said fixed bearing means, motor means operatively connected to said lifting and lowering means and operable simultaneously with and independently of the rotative movement of said roller means, and adjustable means operable by said base member for selectively varying the amplitude of said tilting movement of said base member.

3. An arrangement for use in connection with the refining of metals in a rotatable reaction chamber, which comprises in combination: a base member, roller means carried by said base member and arranged for rotative movement for rotatably supporting said reaction chamber, first bearing means tiltably supporting one end portion of said base member to allow tilting of said base member about an axis transverse to the axis of rotation of said roller means, second bearing means spaced from said first bearing means in longitudinal direction of said base member, casing means pivotally supported by said second bearing means, a threaded spindle linked to the other end portion of said base member, a worm wheel rotatably journaled in said casing and having a hollow internally threaded hub section threadedly and adjustably engaging said threaded spindle, a worm meshing with said worm wheel, variable speed reversible motor means operable to drive said worm independently of and simultaneously with a rotative movement of said roller means, and reversing means respectively arranged for alternate automatic actuation at the respective desired end of each tilting movement of said base member for reversing the direction of operation of said motor means.
